UNITED STATES PATENT OFFICE

ERIC DOUGLAS TOBIAS NORRIS, OF HOLLINWOOD, ENGLAND, ASSIGNOR TO FERRANTI INC., OF NEW YORK, N. Y.

LIGHTNING OR SURGE ABSORBER

Application filed October 19, 1929, Serial No. 400,957, and in Great Britain December 6, 1928.

This invention relates to lightning or surge absorbers of the type embodying a primary element comprising a winding for connection in series with the line and a 5 metallic element associated with said winding.

The winding and the metallic element associated therewith may be regarded respectively as the primary and short-circuited secondary of a transformer.

Hitherto it has been the general practice to construct such devices in cylindrical form with cylindrical coils, providing the casings in the larger sizes with radial cooling fins. 15 Such devices may be oil filled or dry as desired.

Now I have found that with such constructions as contain oil provision must be made for the expansion and contraction of 20 the oil with temperature changes. The provision of conservators with breather devices as is customary in electric transformer practice is undesirable since lightning or surge absorbers are usually mounted up a pole 25 and are comparatively inaccessible.

Oil is desirable for two reasons, viz., for insulating purposes where the voltage is not fairly low and for heat dissipation purposes where the current is appreciable.

30 One object of the present invention is to provide constructions wherein the necessity for such conservator and breather device in oil-filled surge absorbers is avoided. Another object is to provide improved constructions both of the oil filled and dry type.

Referring to the accompanying diagrammatic drawing:—

Figure 1 illustrates a side view of one convenient construction in accordance with the 40 present invention.

Figure 2 illustrates a horizontal sectional view thereof.

Figure 3 illustrates a vertical sectional view of a modified construction.

45 In carrying the invention into effect in one convenient form illustrated by way of example in Figures 1 and 2, I provide two flat spiral line coils *a*, *b* separated by a sheet or sheets of insulation material *s* and disposed within a substantially square flat cas-

ing *d*, a layer or layers of insulation material *q* being interposed between the casing sides and the coils. Connecting leads are taken from the outer ends of the two coils respectively through diagonal corners of the 55 casing and the coils are connected together electrically at their centres at *r*.

The casing is provided with a suspension ring *e* at one of the remaining corners and is completely filled with oil. The space at 60 the centers of the coils is filled by inserting a disc or discs of wood *c*.

According to this construction expansion and contraction of the oil is taken care of by the sides of the casing *d* which act as expanding diaphragms. Thus, the necessity for a conservator and breather device is 65 avoided.

Furthermore, very little oil is required in comparison with that needed in the single 70 layer cylindrical type of surge absorber and this is further reduced by the provision of central disc or discs *c*.

Also, there is no large waste space, as is the case in the ordinary cylindrical type 75 of absorber. Overall bulk is thus considerably less, with decrease in cost.

Again, owing to the comparatively small dimensions in the horizontal direction erection conditions do not impose a limitation 80 on the design.

Again, a primary winding embodying elements having a plurality of layers in one plane is more efficient as an inductance than a coil of the single layer cylindrical type. 85 Thus, for a given inductance value less material is required than in the latter.

Again, since the external leads *f* are brought out from substantially the same plane as the coils their insulation is of extremely simple nature.

A similar form of construction may be employed in respect of a non-oil-filled lightning or surge absorber.

As regards cooling, we prefer to provide 95 vertical cooling fins *o* on the exterior of the casing which are much more effective than the radial fins employed on cylindrical surge absorbers owing to the unrestricted path for the air. The cooling of the actual wind- 100

ings when oil is employed may be performed by the natural convection of the oil, through suitable oil ducts, and this again is more effective in constructions according to the present invention than hitherto practicable.

If oil ducts be not provided, oil nevertheless improves cooling by displacing the air from the spaces between the sheets of insulation (oil having a thermal conductivity 10 many times greater than air).

According to a modification as illustrated in Figure 3 the coil construction is somewhat similar to that described above except that only two layers of windings are employed 15 in a single plane. The insulation on the conductor may be, however, sufficient for the insulation between conductor and dissipator as well as between conductors.

Insulators *g*, *g* are at right angles to the 20 plane of the coil elements instead of in the same plane as before. The absorber consists of three pairs of elements connected electrically in series. Between each pair of coils and the adjacent pair a washer of dissipating material *h* is inserted, washers *k* and annular rings *m* together forming the case and secondary winding of the absorber. The washers *k* are furnished with vertical 25 cooling fins *o*'. The annular rings *m* are welded to the washers *h* and *k* at points *n*. Ample provision is therefore given for expansion.

In order to increase the electrostatic capacity of absorbers in accordance with the 30 present invention the conductor may be coated or covered with metal foil or metallized paper. Such conductor covering will improve the heat dissipation of the absorber, and if of suitable material bring the energy 40 dissipated into closer association with the conductors.

The forms of construction described above 45 are given by way of example only and may be modified.

For instance, it is not essential that the flat sheets of metal associated with the line winding be sheets having actually plane surfaces, since corrugated sheets may quite 50 effectively be employed and in fact in oil-filled lightning or surge absorbers would impart still greater flexibility for dealing with the expansion and contraction of the oil.

I claim:

1. A lightning or surge absorber including 55 a primary element comprising a substantially flat spiral winding for connection in series with the line subject to lightning or other electrical surges disposed between two 60 flat metal flexible surfaces forming part of the secondary element casing for the purposes set forth.

2. A lightning or surge absorber as 65 claimed in claim 1 including a core of insulating material disposed at the centre of

the coil in order to reduce the required oil content of the casing.

3. A lightning or surge absorber as claimed in claim 1 including terminals and external leads disposed at right angles to the 70 plane of the coil.

4. A lightning or surge absorber as claimed in claim 1 including also vertical cooling fins for said casing.

5. A lightning or surge absorber as 75 claimed in claim 1 wherein said casing is formed of two circular metal disks spaced apart by an annular ring of substantially U-section.

In testimony whereof I have signed my 80 name to this specification.

ERIC DOUGLAS TOBIAS NORRIS.
